HEAT-TREATING FURNACE TRAY

Henry H. Harris, Champaign, Ill.

Application November 16, 1937, Serial No. 174,775

3 Claims. (Cl. 263—47)

My invention relates to work supports, commonly called trays, for use in heat-treating furnaces.

Conventionally, articles to be carburized are disposed within containers or boxes also having therein a carburizing compound, the container or carburizing box being sealed and placed within a furnace or muffle and subjected to high heat, and the carburizing effected under the influence of the heat. While the supports or trays of the present invention could be used for supporting such carburizing boxes, during travel through the furnace they are preferably made use of in furnaces and with heat treatments wherein the articles to be treated are placed or loaded directly upon the supports or trays which are traveled, as by being pushed in tandem, through the furnace, muffle or the like so as to be directly exposed to the heat and furnace gases, preferably carbonaceous gas.

This carbonaceous gas is a saturated hydrocarbon, and when it comes into contact with the articles being treated, it is apparently cracked and deposits a certain amount of soot on both the articles or work being treated and the support of tray upon which the work is carried. Normally this soot is harmless, but if there are any imperfections, such as cracks or shrinks, either deep-seated or of superficial nature, in the alloy material of which the trays are usually made, the gas will enter therewith and deposit its carbon. At the time of this deposit, the tray is being subjected to high heat and is therefore largely expanded. Upon removal from the furnace, however, the trays come into contact with a cooler atmosphere and a shrinkage occurs. This shrinkage contracts the metal around the soot or deposited carbon, and what was originally a barely discernible crack or fissure and relatively insignificant becomes larger and more clearly defined. Upon repetition of this process and consequent subjection of the tray to the action of heat, carbon deposit, and cold, the cracks or fissures may reach such proportions as to result in the virtual destruction of the trays as a usable article.

The conventional trays used in this type of furnace operation have been of skeleton or open-work formation, rather than continuous sheets or cast imperforate members. There are several reasons for this, namely, that to obtain optimum results in the heat-treatment process it is necessary that as much of the surface area of the article being treated as is possible be exposed directly to the furnace heat and this can best be

effected with use of an openwork support; also, the skeleton formation necessitates the use of less metal and hence a lighter and cheaper product can be obtained.

These openwork trays are usually one-piece castings and necessarily contain a large number of intersections, that is, points where the bars cross and there is a greater thickness of metal at and about the intersection than through the bars themselves. Experience has shown that the imperfections occur principally at these thicker points because of strains set up during the heating and cooling operations, which imperfections subsequently develop into destructive cracks and fissures. The present invention is directed to the solution of the problem of avoiding or reducing difficulties such as are referred to above.

In operation, the trays or supports have loaded thereon the various articles to be heat-treated, and the loaded trays are usually pushed through the furnace in tandem, that is, a number of trays, similarly loaded, are placed within the furnace and pressure applied against the rear-most thereof to push the trays through the furnace, each tray communicating the pressure to the one in front. The heated trays are thus subjected to stresses in two transverse planes, namely to load-bearing stresses in the vertical plane and to compression stresses of the travelling pressure in the horizontal plane. During normal furnace operation, these stresses also cause a great many tray failures since they tend to develop the ultimately destructive cracks or shrinks, and cause buckling and bending. It is also an object of my invention, therefore, to provide a tray which will have a greater load-bearing capacity in conjunction with increased ability to resist compression stresses.

It is a further object of my invention to provide a heat-treating furnace tray with means incorporated therewith to directly take the compressive, travelling stresses.

It is a further object of my invention to provide a heat-treating furnace tray having a substantially flat top with openings to allow free passage of heat therethrough.

Other and related objects will in part be obvious and in part be pointed out specifically in connection with the following description of an illustrative embodiment thereof.

Figure 1 is a plan view of one form of device constructed according to and embodying my invention.

Figure 2 is a side view thereof, partly in sec-

55

tion and partly in elevation, along the broken line 2—2 of Figure 1.

Figure 3 is an end view thereof, also partly in section and partly in elevation, along the broken line 3—3 of Fig. 1; and

Figure 4 is a section along the broken line 4—4 of Fig. 1.

Reference numeral 10 indicates the tray generally, which is usually a one-piece casting of preferably nickel-chromium-iron alloy steel.

Tray 10 is preferably rectangular in shape, the front, back and side edges thereof being substantially straight. Tray 10 comprises flat top portion 12 and substantially flat bottom portion 14. Portions 12 and 14 are the same length from front to back of the tray, but bottom 14 is narrower than top 12 from side to side thereof; see Fig. 2. Top 12 and bottom 14 are spaced apart and centrally connected by interior wall 16, which defines a central well opening 17, also substantially rectangular in shape, through tray 10. This interior wall 16 at right angles to the plane of the tray top and bottom gives increased load-bearing strength to the tray. Top 12 and bottom 14 are also connected in the spaced-apart relationship by the inclined walls 18, 19 which extend from the edges of top 12 to the edges of bottom 14, at both sides of the tray. The space between top and bottom portions 12, 14 is left open at the front and back 30 of the tray, as shown in Fig. 2 at the right. In this respect the tray generally resembles a flattened tube having a transverse opening therethrough.

A plurality of openings 20 are provided in the upper tray portion 12, which are preferably in registry with a similar number of openings 22 in bottom portion 14. Openings 20, 22 are shown in registry, but they need not be, as for example, the openings might be in any desired staggered arrangement. Openings 20, 22 are provided to present as much of the surface of the work being treated as possible, and also to allow the heat to pass through the tray. These openings, together with central opening 17 and the spaced-apart relationship between the tray top and bottom, will allow the heat generated within the furnace to pass through the tray and reach and act upon work supported by the tray during passage through the furnace.

Upstanding walls 24, 26 are provided at the front and back of the tray, as are walls 28, 30 at the tray sides, to form retaining members to keep the articles placed on the tray from falling off therefrom during tray travel through the furnace.

Walls 28, 30 are preferably formed by providing an upwardly rounded union between the inclined wall portions 18, 19 and the top member 12. Upstanding lugs 31 are provided at separated points on the upper surface of member 12 to assist in retaining work in predetermined position on the tray.

The bottom 14, while generally domed or arched downward for strength, has widely separated flat underside portions 32 along the sides thereof to provide wearing surfaces which bear on rails 34 on which the tray is travelled through the furnace. The junction of the inclined walls 18, 19 with the floor member 14 are so formed as to pro-

vide downwardly extending retaining flanges 36 at right angles to portions 32, which flanges 36 serve to keep tray 10 in line on tracks 34. If desired, rollers or tracks with rollers (not shown) may be used to cooperate with my form of tray for travel through the furnace.

Over the bearing portions 32, a pair of H-beams 50, 50 equal in length to the length of tray 10 from front to back, are inserted in the space between top 12 and bottom 14, substantially filling said space, and secured in this position within the tray by rivets 52. A plurality of lugs 54 are provided in the underside of top 12 and the upper surface of bottom 14 forming guide members to keep beams 50, 50 in position. H-beams 50, 50 are incorporated into the tray at those points of the tray which overlie rails 34, because it is at these points that the tray travelling pressures are applied and the compression stresses are at their maximum. Beams 50, 50 not only take up and absorb the compression stresses, but also, since they substantially fill the space between the tray top and bottom, take up some of the load-bearing stresses, and in this regard the H-beams serve a double function. In the form shown, H-beams 50 are utilized, but any other form of beam may be used, if desired, which will serve the same purposes.

My invention combines the strength of a solid tray with the lightness of a skeleton form tray, and by virtue of its particular construction is enabled to better resist the tray-travelling compression stresses and the load-bearing stresses and thus have a longer operative life.

Having now described my invention, what I claim and desire to secure by Letters Patent is:

1. A tray for use in heat treating furnaces comprising a top portion and a bottom portion, said portions being equal in length from front to back of the tray, and said bottom portion being shorter than said top portion from side to side of the tray, and means to secure said portions in spaced-apart relationship comprising a pair of inclined walls extending from the sides of the top portion to the sides of the bottom portion.

2. A tray for use in heat treating furnaces through which trays are travelled on rails in tandem comprising a top portion, a bottom portion on which the tray is travelled through the furnace spaced from the top portion, a pair of thrust transmitting and load supporting beams disposed therebetween, means formed integral with the top and bottom portions to keep the beams in place and means to secure the top portion and the bottom portion in said spaced relationship.

3. A tray for use in heat treating furnaces through which trays are travelled on rails in tandem comprising a top portion, a bottom portion on which the tray is travelled through the furnace, which bottom portion is spaced from the top portion, and a plurality of separate thrust transmitting and load supporting members disposed and secured within the tray extending from front to back thereof between the spaced-apart top and bottom portions.

HENRY H. HARRIS.
